UNITED STATES PATENT OFFICE.

CLEMENT D. HELLYER, OF LOS ANGELES, CALIFORNIA.

REPORTING TOOL.

Application filed June 9, 1924. Serial No. 718,754.

This invention relates to cutting machines.

The general object of the invention is to provide a reporting tool which is adapted for operating on the valve seats of internal 5 combustion engines.

Another object of the invention is to provide a reporting tool including a handle and cutting members wherein improved means is provided in the handle for moving the cutting 10 members to cut holes of different sizes.

Other objects of the invention will be apparent from the following description taken in connection with the accompanying drawings wherein Fig. 1 is an elevation of an assembled reporting tool; Fig. 2 is a central sectional view of the tool; Fig. 3 is an end elevation of the tool; Fig. 4 is a section on line 4—4, Fig. 2; Fig. 5 is a section showing the tool in elevation and wherein the tool is being inserted in position; Fig. 6 is a view similar to Fig. 5 showing the tool ready for the cutting operation; Fig. 7 is a sectional detail, partly in elevation, showing the manner in which the tool is assembled; Fig. 8 is an end view of the tool with the closure cap removed and Fig. 9 is a perspective view of a cutting knife.

Referring to the drawing by reference characters, I have shown a reporting tool, embodying the features of my invention, at 30 10. This tool comprises a body portion 11 having a central aperture 12 therethrough. The body is provided with an enlarged head as at 14 adjacent one end and at the other end is provided with a flat shoulder 15 for engagement by an indicating member to be presently described. Intermediate the ends of the body portion, I provide a rectangular portion 16 which may be engaged by a wrench for turning the tool.

The body portion is shown as provided with opposed apertures 17 which are adapted to be engaged by the threaded extremities of handles 18. The enlarged head 14 of the tool is shown as provided with opposed slots 20. Each of the slots 20 is defined by parallel side-walls as shown. Mounted to slide in the slots 20 I show a pair of cutting knives 21. These knives are adapted to have a tight sliding fit within the slot 20 and on their opposed faces are shown as provided with racks 22, for a purpose to be later described. The cutting knives 21 carried by the head 14 are provided with sharpened portions at both ends so that by turning the knives over and turning them end for end both extremities may be used for cutting.

The head 14 is shown as provided with a cap 25 which is in the nature of a closure cap. The cap 25 is shown as provided with a depending skirt 26, which may be slotted as at 27 to receive the protruding portion of the knives 21. The skirt 26 and the cap 25 serve to hold the cutting knives firmly in position. The cap 25 may be secured in place by suitable screws 27', or in any other desired 65 manner.

My reporting tool is particularly adapted for operating on valve seats of internal combustion engines. These valve seats frequently are arranged in a cavity, the opening to which is smaller than the diameter of the valve seat. As a consequence, it is impossible to insert the usual cutters within the cavity since any cutter which is large enough to make the desired 70 cut is too large to pass through the opening 75 to the cavity.

In order to provide means to center the tool, I provide a pilot or guide 28 which is shown as removably secured to the cap 25. By providing a set of pilots 28 with each tool, the operator will have the correct pilot to fit any 80 valve stem aperture.

In order to hold the knives 21 in position and to adjust them laterally for making the correct cut, I show the body 10 as provided 85 with a central operating member 30. This operating member 30 is shown as provided with a pinion 31 adjacent its lower end. This pinion 31 as shown in Fig. 7 engages the opposed racks 22 on the knives 21. The operating member 30 is provided with a head 33 thereon which may be secured to the operating 90 member by a suitable pin 32.

The end of the operating member 30 opposite the pinion 31 is provided with a reduced 95 portion 34 which is adapted to receive an adjusting knob 36 as shown. The adjusting knob 36 may be a cap member which may be threaded on the portion 34. To prevent turning of the adjusting knob, I show a set screw 100 37 which is adapted to fit against a flattened portion near the end of the operating member 30.

In order to cut a number of valve seats of the same size it is desirable that indicating 105 means be provided to quickly and readily indicate the relative adjustment of the cutting knives 21. To do this, I provide a gauge ring or indicator, 40. This is secured for longitudinal movement on the operating member 30. The gauge ring 40 is provided with a key 110 41 which engages in a keyway 42 in the oper-

ating member 30 so that the dial will slide longitudinally on the operating member 30 but will be prevented from rotary movement thereon. The ring 40 is provided with a scale 5 41' thereon while the body portion 10 is provided with a zero mark 42 thereon. In order to hold the gauge ring 40 in adjusted position with a correct reading of the scale and also to hold the knives 21 against lateral movement, 10 I provide a lock nut 45. This lock nut is threaded on to the end of the operating member 30 and is provided with plane surface which is adapted to engage the adjacent portion of the gauge ring 40. The upper and 15 lower surfaces of the ring are plane so that it will be apparent that when the lock nut is rotated in the proper direction, the gauge ring 40 will slide along its keyway and will tightly engage the shoulder 15 on the body 10 to thus 20 firmly lock the cutting knives in position.

In operating the device to cut a valve seat, the lock nut is released and the knob 36 is turned so that the knives are moved inwardly. The reporting tool is then inserted through 25 the aperture and is brought adjacent the valve seat. After this is done the adjusting knob 36 is rotated in the proper direction until the correct reading on the scale 41 appears. This being done the lock nut 45 is tightened to secure the knives in position. After this is done 30 the workman grasps the handles 18 and performs the necessary cutting operation. If desired, the device may be turned by a wrench which engages the rectangular portion 16, instead of turning the handles 18.

After the cut is made, the lock nut is released and the adjusting knob operated to reduce the diameter of the tool so that it can be removed and will be ready for another 40 operation.

Having thus described my invention, I claim:

1. In a cutting tool, a handle, an enlarged head on said handle, a cap removably secured

to said head, said cap having a skirt thereon 45 surrounding said head, an enlarged recess in said cap, a pilot removably secured on said cap, a hole extending through said handle, a pair of transverse slots in said head and aligning slots in said skirt of said cap, a cutting 50 knife in each of said slots, said cutting knives each having a rack on one face thereof, an operating rod, said operating rod being positioned in said hole and having at one end a pinion adapted to engage said racks on said 55 knives, an enlarged head on said rod, positioned in said recess of said cap, said rod head being adapted to engage the under face of each of said knives to hold said knives in adjusted position against the head of said handle, a ring keyed to slide along one end of said rod, a threaded lock nut on said rod above said ring, said lock nut adapted to force said ring against said handle to hold said knives in adjusted position and an enlarged knob 60 on said rod above said nut for turning said rod to move said knives.

2. In a cutting tool, a handle having a hole extending therethrough, said handle having an enlargement at one end thereof, a pair of transverse slots in said enlargement, a cutting 70 knife in each slot, an operating rod extending through said handle, an enlarged head on said rod adapted to engage the under side of said knives, said rod having means thereon adapted 75 to move said knives, a ring keyed to slide along one end of the rod, a threaded lock nut on said rod, said lock nut being adapted to force said ring against said handle to hold said knives in adjusted position and clamp 80 said knives between said rod head and said enlargement, an operating knob on said rod, said enlarged portion having a cap fitted thereover, and a pilot secured on said cap.

In testimony whereof, I hereunto affix my 85 signature.

CLEMENT D. HELLYER.
